UNITED STATES PATENT OFFICE

2,236,989

VACUUM CLEANER

Gustaf Erik Bjorkman, Stockholm, Sweden, assignor to Electrolux Corporation, Dover, Del., a corporation of Delaware

Application March 19, 1938, Serial No. 196,836
In Germany March 19, 1937

1 Claim. (Cl. 15—158)

My invention relates to vacuum cleaners and more particularly to an improved brush nozzle for a vacuum cleaner.

In accordance with my invention there is provided a nozzle having a hollow body formed with an elongated suction opening and within which body there is arranged a brush member so mounted that it can slide back and forth transversely of the elongated opening as the nozzle is moved back and forth over a surface to be cleaned. Consequently, the brush is always in contact with the trailing lip of the nozzle and the dirt which the brush dislodges from the surface and tends to push before it is caught by the air stream entering the nozzle and is conveyed away thereby.

A further feature of my invention resides in the fact that the brush member is removably mounted within the nozzle body, whereby it may be readily removed when it is desired to use the nozzle without the brush.

Further objects and advantages of my invention will be apparent from the following description considered in connection with the accompanying drawing, which forms a part of this specification and of which:

Fig. 1 is a front view, partially in cross-section, of a nozzle in accordance with my invention;

Fig. 2 is a bottom view of the nozzle shown in Fig. 1;

Fig. 3 is a cross-sectional view taken on the line 3—3 of Fig. 1; and

Fig. 4 is a cross-sectional view showing another embodiment of my invention.

Referring to the drawing, reference character 10 designates a hollow nozzle body formed with a suction inlet opening 11 which opening is bounded by a forward lip 12, a rear lip 13 and end lips 14. The upper wall of the hollow body is formed with an outlet opening 15 which communicates with a connection member 16 adapted to connect the nozzle to a source of suction by means of a hollow conduit 17.

Secured to the end lips 14 within the hollow body are guide rails 18 which are provided with grooves for receiving members 19 which are secured to the opposite ends of a brush member 20. The brush member includes a rigid back 21 to which are secured bristles 22. The length of the bristles is such that they extend downwardly through the inlet opening 11 so as to contact a surface to be cleaned. The width of the brush member 20 is substantially less than the width of the suction opening 11.

In operation, when the nozzle is moved back and forth over a surface to be cleaned, in the di-

rections indicated by the arrows in Fig. 3, the friction between the ends of the brush bristles and the surface causes the brush member to lag behind the nozzle until the member is contacted by 5 the trailing lip of the nozzle. Thereafter, the brush moves over the surface along with the nozzle. If the nozzle is moved to the right, as viewed in Fig. 3, the rear lip 13 constitutes the trailing lip and the brush member 20 is contacted by this lip. Consequently, dust and dirt removed 10 from the surface by the brush bristles, and which is pushed along ahead of the bristles, is caught up by the air stream entering the suction opening 11 and is carried thereby through the outlet opening 15, the connecting member 16 and the conduit 17 to a vacuum cleaner unit. When the nozzle moves to the left, as viewed in Fig. 3, the forward lip 12 becomes the trailing lip and the brush member 20 is contacted thereby and the same cleaning 15 action results as above described.

As will be seen particularly from Fig. 2, when the brush member 20 is in either of its extreme positions, it is disposed entirely to one side of the outlet opening 15, whereby it does not interfere 20 with flow of air through this opening.

In a suction nozzle, a hollow body having at guide rails 18 are made of resilient material whereby they may be sprung toward the end lips in order to release the members 19 from engagement therewith, thus making it possible to easily remove the brush member 20 from the nozzle body. The operation of the embodiment shown in Fig. 4 is the same as that above described.

While I have shown two more or less specific 35 embodiments of my invention, this has been done for purposes of illustration only and is not intended to limit the scope of my invention, which is to be determined by the appended claim viewed in the light of the prior art.

What I claim is:

In a suction nozzle, a hollow body having an elongated suction opening adapted to be moved back and forth over a surface to be cleaned in a direction substantially at right angles to the lengthwise extent of said suction opening, a brush member extending lengthwise of said opening and having bristles projecting outwardly through said opening to contact said surface, the width of said brush member being substantially less than the width of said suction opening, guide rails secured within said body adjacent to the ends of said opening and extending transversely thereof, an means secured to the ends of said brush member and engaging elongated slots in said guide rail

for supporting said member within said body for sliding movement back and forth across substantially the entire width of said opening in a plane parallel to the plane of said opening and for limiting movement of said brush member to a direction transverse to said suction opening, said guide

5 rails being resilient and the slots being located in portions of the guide rails spaced from said body, whereby said rails are deformable to disengage said means therefrom in order to remove said brush member from said nozzle.

GUSTAF ERIK BJORKMAN.

CERTIFICATE OF CORRECTION.

Patent No. 2,236,989.

April 1, 1941.

GUSTAF ERIK BJORKMAN.

It is hereby certified that error appears in the printed specification of the above numbered patent requiring correction as follows: Page 1, second column, line 26, strike out the words "In a suction nozzle, a hollow body having an" and insert instead --In the embodiment illustrated in Fig. 4, the--; and that the said Letters Patent should be read with this correction therein that the same may conform to the record of the case in the Patent Office.

Signed and sealed this 29th day of April, A. D. 1941.

(Seal)

Henry Van Arsdale,
Acting Commissioner of Patents.
